UNITED STATES PATENT OFFICE.

EMERSON A. BOLEN, OF MORRIS, ILLINOIS, ASSIGNOR TO THE NORTHWESTERN CORPORATION, OF MORRIS, ILLINOIS. A CORPORATION OF ILLINOIS.

STAMP-VENDING MACHINE.

1,419,353.

Specification of Letters Patent. Patented June 13, 1922.

Application filed August 17, 1921. Serial No. 492,914.

To all whom it may concern:

Be it known that I, EMERSON A. BOLEN, a citizen of the United States, residing at Morris, in the county of Grundy and State 5 of Illinois, have invented certain new and useful Improvements in Stamp-Vending Machines, of which the following is a specification.

In the construction of stamp-vending machines I have found it to be very difficult 10 to provide any mechanism that will satisfactorily operate to deliver five postage stamps on a single operation of a manually moved actuator. Stamps, as supplied in rolls suit-

15 able for use in coin-controlled vending machines, vary materially in length between perforations, and in the handling thereof it is desirable to employ, as a means for automatically compensating for such variation,

20 a polygonal stamp driver or feed wheel cooperating with a fixed arcuate retaining wall, in embodiment of the invention set forth in my prior Patent 1,199,961. My present invention has for its object to provide 25 a specific application of the polygonal driver principle in conjunction with the arcuate wall that will satisfactorily handle the difficult matter of delivering five stamps for each half rotation of the driver, practically

30 regardless of wide variations in spacing between the perforation rows of the stamp strips. To this end it consists in the construction and arrangement hereinafter set forth and claimed.

35 In the drawing Fig. 1 is a diagrammatic section through a stamp-vending machine embodying my present invention, and Fig. 2 is a perspective detail of a stamp-delivering wheel or driver.

40 In the casing 10 having a stamp-delivery orifice 11 that preferably is supplemented on one side by a guide roll 12 and on the other side by an internally projecting wire finger or "curler" 13, the polygonal driver 14 of a 45 thickness approximately equaling the width of a stamp strip is mounted on a horizontal shaft 15, the driver being operatively associated with an arcuate guard or retainer 16 that is suitably fixed in the casing concentrically 50 with the shaft 15, the driver having a perimetral median slot into which the curler finger 13 dips and being provided at its corners with break-ridges 19 each preferably having one or more shallow pins 20 protrud-

ing very slightly therebeyond. The stamp-strip 55 21 leads from a roll 21' over guide-rollers 22 and 23 into the opening 24 of the arcuate retainer wall 16, the receptive edge 25 being preferably close to the roller 23 and the stamp strip passing over such roller 60 being borne upon by a light tension spring 26, secured to the casing. The opening 24 through the retaining wall is preferably less than 90 degrees in extent, and the stamp strip, passing around the driver 14 between 65 its break-ribs 19 and the retaining wall 16, emerging past the end 27 of said wall close to the guide roller 12.

Suitable provision is made for coin-controlled rotation of the driver to the extent 70 of a one-half revolution for each operation of an actuating handle. Since mechanisms that will accomplish such a result of accurate predetermined throw of a driver under coin control are well known, I merely illustrate 75 diagrammatically the presence of structure for the stated purpose and for which more refined mechanism may obviously be substituted. In the schematic showing a coin 30 introduced through coin 80 chute 31 may be picked up by a carrier arm 32 loosely rotatable about shaft 15 and operable by the handle 33, the coin when picked up by such arm 32 being rotatively carried by the arm under the guidance of an arc 34 until 85 it reaches the end of said arc and falls from the carrying arm, and the driver 14 having secured thereto as by screw 35 a two-armed yoke the diametrically opposed fingers 36 of which stand in the path of travel of the coin 90 to be carried in half rotation during the traverse of the coin from receptive position to delivery position.

In constructing the polygonal driver for five-stamp delivery I form its surface in 95 six chords, four of these being each of approximately two-stamp length and two of them being each of one-stamp length, with the one-stamp chords in diametrically opposed position. In measuring chord lengths 100 from tip to tip of the pins 20 of the breaker-ribs,—and it is in respect of the outermost points of the structure that chord-lengths should be determined—I calculate stamp-length by the maximum measurement that 105 I find to be at all commonly encountered in the separation between perforations in stamp-rolls, and in relating the driver 14 to

the arcuate retaining wall 16 I provide clearance slightly in excess of the thickness of the gummed stamp strips.

By constructing in the manner described, using a hexagonal polygon with two short sides and four long sides I am able to relate contiguous faces throughout the structure at sufficiently abrupt angles to give a sharp bending or breaking tendency, or, in other words, I ensure that the stamps of the strip, tending always to bend at the lines of perforation, may lie in chords within the arc of the retaining wall presenting a rather abrupt angle between adjacent chords of the stamps. In resultant practice it is the fact, as graphically suggested in Fig. 1, that the driver normally standing in the position shown in Fig. 1, so that the previously-delivered batch of five stamps will have been torn off at the line of perforation closest to the leaving end 27 of the retaining wall, the stamp 21^a lying between this point and the next point on the driver (that is to say, lying on the one-stamp chord of the driver) may not have its perforation line, at which the rather-stiff gummed stamp strip has angularly broken, in precise register with the breaker-rib or pins of the corresponding angle of the driver, because the stamp may not be of maximum length. Correspondingly, the pair of stamps 21^b, probably of less than maximum length between perforation, may break at a row of perforation quite materially in advance of the driver-angle that lies between two two-stamp spaces, and this lack of register may progressively continue throughout the perimeter of the driver. When, however, the driver is rotated its leading angle, in this case the angle X, will slip forward without driving the stamp until it engages a break in the stamp strip and row of perforations, and will then carry the stamps forward until it passes out of register with the retaining wall 16, when the next angle or corner, Y, will slip forward to its stamp-strip-break and then subsequently the third corner Z will correspond-

ingly make its compensatory slip, so that after the half rotation and delivery of five stamps the stamp-strip may always be readily torn off at the line of the break in the stamp strip registering with said point Z.

It will now be clear that since the important automatic compensatory action of the driver in respect of the stamp depends, for prevention of over-doing the matter and permitting the driver idly to slip inside of the stamp-strip, upon there being a rather abrupt break or angle in the stamp strip at the appropriate line of perforation, and also that there shall be a large enough number of points of cooperation between the stamp strip and the driver to give a material tendency for the stamp strip to be retarded by the encompassing wall 16, notwithstanding that the spacing between the driver-point and the wall is slip-permissive, the hexagonal driver accommodates itself to these conflicting conditions and accomplishes a result difficult of achievement in a manner that is at once simple and effective.

I claim:

1. In a stamp dispensing machine, the combination of a hexagonal driver, means for rotating the same, and a fixed arcuate retaining wall partly encircling the driver and slightly spaced from the effective points of angles of the latter, said driver having the chords between its effective angles arranged to provide two diametrically opposed chords of single-stamp length and the intervening chords each of two-stamp length.

2. A structure as set forth in claim 1 wherein the driver-rotative means is arranged at each operation to move the driver through a half rotation and the retaining wall is provided with an opening of approximately the length of a two-stamp chord, said driver being arranged when in normal position to present the forward angle of a one-stamp chord in cooperation with the leaving-extremity of the retaining wall.

EMERSON A. BOLEN.
